J. H. HANCOCK

WRENCH

Original Filed Dec. 4, 1920

witness

James F. FitzGibbons

Joseph Heber Hancock INVENTOR

BY

ATTORNEY'S

UNITED STATES PATENT OFFICE.

JOSEPH H. HANCOCK, OF MURRAY, UTAH.

WRENCH.

Refiled for abandoned application Serial No. 428,249, filed December 4, 1920. This application filed March 28, 1927. Serial No. 179,151.

This invention relates to new and useful improvements in wrenches.

One object of the invention is to provide a wrench which is simple in construction, 5 and which can be manufactured at a low cost.

Another object is to provide a wrench which is formed from few parts, and which is strong and durable in operation.

10 A further object is to provide a wrench wherein the stationary jaw of the pipe engaging portion is formed for use in drawing nails and tacks.

Other objects and advantages will be apparent from the following description when taken in connection with the accompanying drawing.

In the drawing:

Figure 1 is an elevation of a wrench made 20 in accordance with the invention.

Figure 2 is an end view looking toward the outer or stationary jaw to show the nail and tack extracting claws thereof.

Figure 3 is an edge view of the wrench 25 looking inwardly toward the pipe jaws.

Figure 4 is a vertical sectional view through the movable jaw on the line 4—4 of Figure 3, showing the manner in which the movable jaw face is mounted and the means 30 for turning the jaw moving screw bar.

Referring particularly to the accompanying drawing, the shank of the wrench is formed from a single length of round bar metal doubled at its intermediate point to 35 produce the longitudinal parallel leg portions 10 which have their outer extremities stationarily secured within openings 11 in the stationary jaw 12 of the wrench. The intermediate portions of the legs 10 of the

40 shank, are offset inwardly, as shown at 13, and the portions beyond such offset portions extending in parallel relation but slightly closer together than the portions at the other side of the offsets, said closer portions being

45 connected by the bight portion 14, and form the hand grip of the wrench. The movable jaw consists of a block 15 having the three openings 16 and 17, formed vertically therethrough, the openings 16 receiving the legs 50 10 slidably therethrough, while the other opening 17 is threaded. Extending between the portions 10, and above the offsets 13,

with openings receiving the legs 10, therethrough, is a bar or plate 18.

In one end of the block 15 there is formed 55 a vertical bifurcation 19 in which is disposed the stem 20 of the movable jaw face of the pipe engaging portion of the wrench. The lower face of the head of the jaw face is double beveled, as shown at 21 and 22, respectively, the portion 21 being arranged to rest on the upper face of the block 15, when the face is engaged with a piece of work, and pressure is exerted thereon, while the other face 22 engages with the upper face of 60 the block, when pressure is relieved and the wrench is being turned for a new grip on the work. 65

Disposed between the legs 10, and in parallel relation thereto, is a threaded bar or 70 rod 23 the outer end being rotatably supported in an opening 24 in the stationary jaw 12, which opening is formed between the openings 11. The other end of the threaded bar is disposed through the center 75 of the plate 18, with its projecting end headed, as at 23', to prevent longitudinal movement of the bar. Secured to or formed integrally with the threaded bar, inwardly of the plate 18, is an enlarged cylindrical, 80 and corrugated or scored member 25 which is grasped to rotate the bar. The bar 23 is threadedly engaged through the central threaded opening 17 whereby upon rotation of the bar the movable jaw or block 15 will 85 be moved longitudinally on the bar and the legs 10, toward or away from the stationary jaw so that the portions 12' and 15' will grip a nut, or the portions 12'' and 15'' grip a round piece of work, such as a pipe or round 90 bar.

Particular attention is called to the extreme simplicity of the wrench, and the fact that it is formed from the minimum number of parts, thus rendering the same easy 95 and cheap to manufacture. It will be noted that the bar from which the legs 10 and hand grip portion are formed, is formed from a single length of metal, thus greatly simplifying the making of the wrench. 100 Furthermore, this bar serves to support both the stationary and movable jaws of the wrench, as well as the member 18 which supports one end of the threaded bar. The said

length of bar metal provides the shank as well as the hand grip of the wrench.

It is to be understood that various changes may be made without the slightest departure 5 from the spirit of my invention.

What is claimed is:

A wrench including a substantially U-shaped shank, a jaw member secured to the outer ends of the legs of the shank, a block 10 slideable on the legs and forming a movable jaw, the legs being offset inwardly intermediate their lengths, a plate receiving the

legs therethrough and resting on the said offsets, and a threaded bar engaged through the movable jaw and having one end rotatably supported in the first jaw and the other end rotatably supported in the plate between the said legs, said bar having a cylindrical enlargement on the last-named end between the movable jaw and the said plate and bearing at all times against the plate. 15 20

In testimony whereof, I affix my signature.

JOSEPH H. HANCOCK.
